VAGINAL IRRIGATOR

John C. Shotton, Lakewood, Ohio

Application March 9, 1945, Serial No. 581,832

4 Claims. (Cl. 128—241)

1

This invention relates to douches and, as shown herein, is especially adapted for use in irrigating vaginas.

It is the general purpose and object of the invention to provide a douche or irrigator which, when used for the purpose specified, will enable the wall of a vagina to be irrigated and/or disinfected in a most effective manner.

A further and more limited object of the invention is to provide an instrument of this character by means of which the wall of a vagina may be dilated, whereby the entire surface of the same may be subjected to a cleansing and/or disinfecting liquid.

Further and more limited objects of the invention will be realized in and through the construction and arrangement of the parts shown in the accompanying drawing, wherein Fig. 1 represents a sectional elevational view of the aforesaid instrument and of the means for supplying and controlling the flow of an irrigating and/or disinfecting fluid thereto; Fig. 2 a sectional view, taken on the line 2—2 of Fig. 1 with a portion of the inflatable jacket broken away; Fig. 3 a sectional view taken on the line 3—3 of Fig. 1; Fig. 4 an elevational view, with parts broken away, of the said inflatable jacket; Fig. 5 an end elevational view of said jacket; and Fig. 6 an elevational view of the screw plug used with the instrument shown in Fig. 1.

Describing the various parts herein by reference characters, 10 denotes generally the body of the douche or irrigator, the said body comprising a rear tapered portion 11 having a shield 12 at the rear or outer end thereof. The front end of the said body is also tapered and comprises a plurality of radially extending ribs 13 providing angular or V-shaped channels 14 therebetween, which channels receive the irrigating liquid from a distributing chamber 15 located centrally of the inner ends of the ribs and at the rear ends of the latter and adjacent to and in front of the rear portion of said body and from outlets 15^a delivering the liquid to said channels. The rear portion 11 of the body is provided with a downwardly and forwardly extending channel 16 for irrigating liquid, formed therein and within a sleeved extension 17 of such rear portion. This channel is contracted at its front or delivery end, as shown at 16^a, and delivers liquid supplied thereto to the chamber 15 at said contracted front or delivery end. The rear portion of the body is also provided with a downwardly and outwardly extending channel 18 formed therein and within a sleeved extension 19, said channel hav-

2

ing its inlet end arranged below the contracted delivery end 16^a of the channel 16 and communicating with the chamber 15 and forming a discharge outlet for the irrigating liquid, the front or discharge end of the channel communicating with the chamber 15 and being located beneath the delivery end of the channel 16. The sleeved extension 19 is provided with a valve 20. A tube 21 is shown as communicating at one end with an elevated receptacle 22 and at its lower end with the end of the sleeved extension 17, the said tube being shown as provided with a clip 23. A discharge tube 24 is shown as connected to the delivery end of the sleeved extension 19.

With the parts constructed and arranged as thus far described, it will be evident that, with the instrument inserted in place and the shield 12 engaging the parts surrounding the exterior of the vagina, an irrigating and/or disinfecting liquid may be supplied through the pipe 21 to the chamber 15 and distributed thence to and through the channels 14 to the surface of the wall to be treated, the pressure being regulatable by elevating or lowering the receptacle 22, as well as by manipulating the valve 20 or the clip 23. It will be evident that, by thus controlling the flow of liquid to and from the douche or irrigator, the pressure of the liquid may be correspondingly varied—from a pressure merely sufficient to rinse the wall of the vagina to a pressure sufficient to dilate the wall to an extent to enable the liquid to contact the entire surface thereof.

As has been pointed out hereinbefore, the delivery end of the channel 16 and the inlet end 35 of the channel 18 both communicate with the chamber 15, the latter channel communicating freely with said chamber. The arrangement of the inlet and outlet channels with respect to the said chamber and the location of the chamber 40 with respect to the rear portion of the body enables the liquid to be delivered into the vaginal cavity near the outer end of the same and to be circulated inwardly (or forwardly of the irrigator) throughout substantially the full length of 45 said cavity before returning to the chamber and being delivered thence through the outlet channel. Thus a free in-and-out circulation of the liquid is obtained, thereby insuring a constant dilution of the contents of the vaginal cavity 50 with water and which contents can escape freely and without any blocking or obstruction.

Where, because of the pressure of the liquid employed, there may be difficulty in effecting a seal against the escape of liquid other than 55 through the channel 18, I have overcome this

difficulty as follows: The surface of the rear portion of the body 11 is unbroken or continuous and is provided with a threaded aperture 25 extending from the channel 16 to the exterior of the body and which aperture is normally closed by a screw plug 26; and I have provided the rear portion 11 of the body with annular grooves 21 and 28 located on opposite sides of the said aperture. These grooves are for the reception of a sleeve 29 of inflatable material, such as rubber, said sleeve having side flanges or beads 30 which are adapted to fit snugly under compression within the grooves 21 and 28. It will be evident that, by applying this sleeve in the manner shown in Fig. 1, having first removed the plug 26, a relatively high pressure of the liquid in the channel 16 will inflate the said sleeve, as shown, thereby providing, with the shield 12, a most effective seal against the escape of liquid except through the channel 18. The restriction of the outlet from the channel 16 enables back pressure to be built up quickly with like rapidity of inflation of the sleeve 29.

While, as stated, the douche or irrigator as shown and described herein is primarily adapted for use as a vaginal irrigator or douche or irrigator, it is evident that, by varying the dimensions of the same, it may be used for the treatment of relatively narrow and deep wounds.

For convenience of description, the part of the instrument bearing the shield 12 has been referred to herein and will be referred to in the claims as the "rear" end or portion while the opposite end will be referred to as the "front" end or portion.

Having thus described my invention, what I claim is:

1. An instrument of the character described comprising a body having a rear portion, and a front portion comprising a plurality of ribs extending forwardly from the said rear portion and providing substantially V-shaped channels between said ribs, the rear portion of the said instrument having an inlet channel and an outlet channel therein with their respective delivery and receiving ends in the front end of the said rear portion, the said instrument being provided with a central distributing chamber in front of and immediately adjacent to the delivery end of the inlet channel and the receiving end of the outlet channel and communicating directly therewith, there being openings extending outwardly from said chamber through the portions of the V-shaped channels between which the chamber is located, means for supplying liquid under pressure to the inlet channel, means for controlling the pressure of liquid within and surrounding the channels between said ribs when the said instrument is in situ, and means carried by the rear portion of the said body adjacent to the rear end thereof, for effecting a seal against the escape of liquid supplied to the said instrument except through the said outlet channel.

2. An instrument of the character described

comprising a body having a rear portion provided with an unbroken curved outer exterior surface and having longitudinally spaced grooves extending around and formed within the said surface, the said instrument comprising also a front portion having a plurality of radial ribs extending forwardly from the rear portion and providing channels between the said ribs, the rear portion of said instrument having an inlet channel therein and also having an outlet channel therein, there being openings for the delivery of liquid from the inlet channel to the channels between the said ribs and the inlet end of the outlet channel communicating with the channels between said ribs, there being a port extending from the inlet channel to the exterior of the rear portion of the said body between the said grooves, a removable closure for said port, a sleeve of inflatable material having the ends thereof fitted within the said grooves, means for supplying liquid under pressure to the inlet channel, and means for controlling the pressure of liquid within and surrounding the channels between the said ribs when the said instrument is in situ.

3. In the instrument set forth in claim 1, the delivery end of the inlet channel being contracted and the inlet end of the outlet channel having a materially greater cross sectional area than the delivery end of the inlet channel and providing with the outlet channel a free and unobstructed outlet for liquid supplied thereto from the said central chamber, and means for controlling the rate of flow of liquid through the outlet channel.

4. In the instrument set forth in claim 1, the inlet channel extending downwardly and forwardly and being provided with a contracted delivery end communicating with the central chamber and the outlet channel extending downwardly and outwardly from the said central chamber and communicating with said chamber through an inlet having a materially greater cross sectional area than the delivery end of the inlet channel and providing with said outlet channel a free and unobstructed outlet for liquid supplied thereto from the said central chamber, and means for controlling the rate of flow of liquid through the said channels.

JOHN C. SHOTTON.
